COMPARTMENTED TICKET BOX

John F. Curto, 5757 College Ave.,
San Diego, Calif. 92120

Filed Mar. 18, 1968, Ser. No. 11,027

Term of patent 14 years

U.S. Cl. D87—1
Int. Cl. D3—99; D9—04

FIG. 1

FIG. 2

FIG. 3

The bottom and rear of the box are substantially plain.

I claim:

The ornamental design for a compartmented ticket box, as shown and described.
